UNITED STATES PATENT OFFICE.

GEORGE B. PUTNAM, OF DETROIT, MICHIGAN, ASSIGNOR TO BURROUGHS ADDING MACHINE COMPANY, OF DETROIT, MICHIGAN A CORPORATION OF MICHIGAN.

ADDING-MACHINE.

1,119,040.

Specification of Letters Patent.

Patented Dec. 1, 1914.

Application filed December 14, 1906. Serial No. 347,843.

To all whom it may concern:

Be it known that I, GEORGE B. PUTNAM, residing at Detroit, in the county of Wayne and State of Michigan, have invented certain new and useful Improvements in Adding-Machines, of which the following is a specification.

Letters Patent No. 825,205, issued July 3, 1906, to Burroughs Adding Machine Company upon the invention of Claiborne W. Gooch, disclose a machine equipped with devices for effecting what is known in the art as a "split". In the machine of said patent a special key is provided which when depressed operates to uncouple adjacent latches of the set or gang usually employed in the well-known Burroughs adding and listing machine for controlling the action of impression hammers. By so uncoupling adjacent latches the automatic tripping of latches from left to right for cipher printing purposes is caused to terminate at a predetermined point. Hence the machine is said to be split into two sections or divisions so that two separate and distinct columns of numerals can be simultaneously printed in one series of operations of the machine. This is found useful *e. g.* where designating numbers or dates are desired in tabulation opposite the several amounts the sum total of which is being accumulated. Gooch's invention made provision for fitting up the machine to be thus split at any point from side to side of the transverse series of denominational recording and registering devices. His invention also provided for splitting the machine at more than one point at the same time so that any extent of subdivision desired might be had. The latter provision of the Gooch invention contemplated the employment of a plurality of special couplings between the hammer-controlling latches and manipulative means for disabling the same in order to effect splits at the desired points. Thus the Gooch invention provided for splitting the machine wherever desired but it did not provide for changing the point or points of split after the machine had been once completely assembled without to some extent requiring a re-assembling of parts.

One object of the present invention is to so equip a machine having the Gooch "split" characteristic as to provide for changing the point of split at will by manipulation with-

out requiring any re-assembling of parts. Thus there may be provided upon the key-board of the machine a manipulative device which can be operated at will to vary the adjustment or relative location or positioning of parts which control the latch couplings.

Reverting to the Gooch invention it extended to the provision of means whereby the printing of a total would be prevented in that section or division of the machine which under a split condition of the machine might be employed merely for the recording of designating numbers or dates. It will be understood that a machine having the Gooch "split" contains the customary accumulator made up of independently movable counting members one for each decimal or denominational place up to the full capacity of the entire key-board and usually one or more beyond. The operation of this accumulator, including transfer or "carrying one" to higher denominational members as lower denominational members reach the limit of their counting capacity, is not affected by the so-called "splitting" of the machine. The character of tabulating work for which the "split" makes provision is seldom if ever such as to run the accumulation in the right-hand division of the split machine so high as to encroach upon that section or division of the accumulator which pertains to the left-hand section or division of the split machine. When this left-hand section or division is employed merely for listing designating numbers or dates of course the accumulation is of no moment. However, it is not generally considered desirable to provide means for disabling the accumulator throughout that part pertaining to this left-hand section or division of the machine as this would entail needless complication. However, it is desirable in order to avoid confusion in recording that the accumulated total of recorded designating numbers or dates be not printed at the foot of the column of such numbers when a total is being taken of the amounts recorded opposite these designating numbers. The Gooch invention provided for preventing operation of the hammers of the left-hand section or division of the split machine in a totalizing operation, but, as in the case of the point or points of split, the extent of hammer disablement depended upon the as-

semblage of parts and in order to vary this some re-assembling was required.

In connection with the above-mentioned provision of the present invention whereby the point of split can be varied at will through simple manipulation, it is proposed to equip the machine with manipulative means for preventing or permitting at will the printing of totals in the left-hand section or division of the split machine whatever may be the predetermined point of split, and this without requiring any re-assembling of parts. Thus there may be arranged upon the key-board of the machine a device whose manipulation at the hands of the operator will determine by adjustment or relative positioning of parts first whether the machine is to operate under what is usually termed a normal condition, that is to say without any split or division, second whether the machine shall be split or divided into sections and the accumulation of each section printed as a total or sub-total footing the respective columns or third whether the machine shall be split or divided into sections and the accumulation of the right-hand section only printed as a total footing the right-hand column of amounts, the accumulated total of the left-hand column of designating numbers being excluded from the printed record.

With these and incidental objects in view the invention consists in certain novel features of construction and combinations of parts the essential elements whereof are recited in the appended claims and a preferred form of embodiment of which is described in detail hereinafter and fully illustrated in the accompanying drawings.

Of said drawings Figure 1 represents in right-side elevation an adding and listing machine of the Burroughs type having the improvements of the present invention embodied therein, the inclosing casing of the machine being shown in section as well as certain cross-rods and shafts and the paper-carriage attachment at the rear; Fig. 2 represents the same machine in top plan view with a considerable portion of the key-board broken away to expose parts beneath the same; Fig. 3 represents partly in right-side elevation and partly in vertical section that portion of the machine with which the parts embodying the present invention are more immediately associated; Fig. 4 is a detail sectional plan taken substantially on the line 4—4 of Fig. 3; Fig. 5 represents in left-side elevation that portion of the machine with which the parts embodying the present invention are more immediately associated; Fig. 6 is a detail plan view embracing the limited area indicated by the line 6—6 of Fig. 5; Fig. 7 is a detail vertical section taken on the line 7—7 of Fig. 2; Fig. 8 is a horizontal sectional detail taken

on the line 8—8 of Fig. 7; Figs. 9 and 10 are views somewhat similar to Fig. 3 though embracing much less parts, these two views illustrating adjustments differing from each other and from the adjustment of parts shown in Fig. 3, as controlled by manipulation of the key-board device which determines under what conditions the machine shall operate; and Fig. 11 is a top plan view similar to the central part of Fig. 7 but on a somewhat larger scale.

The invention is here shown by preference embodied in an adding and listing machine of the well-known Burroughs type an example of which is to be found in said Gooch patent and for other details of which reference may be had to the William S. Burroughs Patents Nos. 504,963 and 505,078 issued September 12, 1893. In view of the disclosures in these and other prior patents owned by Burroughs Adding Machine Company and also the presence on the market of the Burroughs machine in large numbers it will not be necessary to extend this specification to a detailed description covering all of the characteristics of said machine. It will suffice to particularize only as to the parts thereof with which the present invention is more closely related. While the embodiment of the invention illustrated in the accompanying drawings is especially adapted to this well-known Burroughs machine the invention is not to be understood as necessarily so limited in its application as it is capable of adaptation to other types of adding and listing machines.

The reference numeral 291 designates the usual amount keys arranged in parallel rows extending from front to rear at the top of the machine and adapted to severally release and set stops for the usual segmental racks 610 which cooperate with pinions 916 of the accumulator 912, the latter being carried in a rocking frame 910. The reference numeral 293 designates the usual total key for timing the movements of said rocking frame when totals or sub-totals are printed, this key as usual surmounting the upstanding portion of one arm of a bell-crank lever 227 secured to a rock-shaft 204 (Fig. 5).

The reference numeral 611 designates the customary arms or levers independently pivoted upon the rocking cross-shaft 600 and carrying at their forward ends the segmental racks and at their rear ends the sets of type-plates 618 respectively. The reference numeral 613 designates the usual restoring frame carried by said shaft 600 and vibrating in each operation of the machine to first retreat from said arms or levers 611 and then restore the same to normal position. The type-plates are as usual driven against a roller platen 1799 journaled in a carriage 1700 which is mounted to shift laterally upon suitable tracks or ways of a bracket

1701 secured to the rear side of the machine casing. Hammers 715 independently pivoted upon a rod 701 strike the type-plates to do the printing, said hammers being actuated by drivers 716 independently pivoted upon a cross-rod 702 and impelled by springs 780, these drivers being normally held against the stress of said springs by a bail 712 also pivoted upon said cross-rod 702 (Fig. 3). This bail is connected through the medium of a link 729 with a plate 823 carried by a rock-shaft 800 which is oscillated in each operation of the machine. Latches 717 independently pivoted upon a cross-rod 700 engage the drivers respectively and pawls 718 operate in the usual manner to severally trip said latches, these pawls being independently pivoted upon the cross-rod of an oscillating bail 704 and yieldingly held in engagement with the latches by the springs 780. The tails of the pawls coöperate as usual with inclined shoulders on the several levers 611 to effect automatic disassembly of pawls when no type-setting movements of corresponding levers 611 take place. It is customary in the Burroughs machine to form the latches 717 with overlapping tails so that there will ensue a tripping or displacement of all latches to the right of that one pertaining to the row of keys representing the highest denominational or decimal place in the amount to be registered and recorded or the total or subtotal to be struck, notwithstanding there may be no type-setting movement of one or more of the levers 611 so located to the right. In the present instance this feature of overlapping tails is entirely omitted and the coöoperative tripping of the latches is accomplished through other instrumentalities. All of these latches have the characteristics of the Gooch special latches in that each is notched in the upper side as shown at 717^a, the notches of adjacent latches being out of transverse alinement. Between each pair of adjacent latches there extends a coupler bar 1315 provided with oppositely projecting studs 717^b to engage the notches of the adjacent latches respectively. These coupler bars are of substantially the same character as the one shown in the Gooch patent and they are similarly engaged with a cross-shaft 1301 being bifurcated to slidily embrace said shaft between spacing collars thereon. Each of these coupler bars thus provides as in the case of the single coupler shown in the Gooch patent for the transmission of tripping movement from the left-hand to the right-hand latch of a pair of adjacent latches. Sufficient free play is allowed for the studs 717^b in the notches 717^a to provide for successive rather than simultaneous tripping of latches from left to right so that the hammers will strike one after another to reduce the shock of impact.

In addition to their sliding movement upon the shaft 1301 the coupler bars may ~~act as~~ as levers on said shaft. They are normally upheld as to their projecting forward ends by springs 1381 connecting them with a fixed rod 1305 as clearly shown in Figs. 3, 9 and 10, these springs thus serving to enforce engagement between the studs 717^b and the notches 717^a. So long as this condition exists throughout the series of latches they will operate the same as though provided with the usual overlapping tails. However, it will be seen that the pivotal mounting of the coupler bars provides for such displacement of any one of them as to discontinue coöoperative relationship between any two adjacent latches.

Passing now to the means for predetermining the point of split by manipulation at the key-board, there is loosely mounted upon a rock-shaft 1302 (located just above and a little to the rear of the shaft 1301) a bail composed of side-arms 1318 and 1319 and a connecting cross-rod 1303 rigidly secured to said side-arms and extending above all of the forwardly projecting arms of the coupler bars or levers 1315 as shown in Figs. 2 and 11. Upon the cross-rod 1303 of this bail there is slidily mounted a disk 1336 which is adapted to move along the rod to a position over any one of said arms of the coupler bars. This disk is in the nature of a presser-foot which may operate upon any one of said arms to depress the same and elevate the studded rear end of the coupler bar thereby disengaging the studs from the notches of adjacent latches. A spring 1383 connecting the bail with a fixed stud below the same (Fig. 3) tends to depress said bail and cause said disk to act in the manner described but such action is controlled by the manipulative device upon the key-board for determining the conditions under which the machine shall operate as referred to at the outset of this specification. The forwardly extending arms of the coupler bars are preferably cut out in their upper edges on a curve as shown to provide for the seating of the disk. For the purpose of sliding the disk along the bail rod 1303 a transversely extending rod 1304 is secured at one end to said disk near its periphery, said rod passing loosely through an arc slot 1308^a in a boss 1304^a on the supporting framework (Fig. 1) and being screw-threaded beyond said boss to receive a thimble 1337 (Fig. 11) to which is attached one end of a cord or cable 1399. A spring 1382 surrounds the rod 1304 between the supporting framework and the disk 1336 and exerts itself to thrust said disk to the left and hold it normally at a position above the extreme left-hand coupler bar as shown in Fig. 11. The cord or cable 1399 passes under a sheave or pulley 1338 (Figs. 1 and 2) suitably supported by the

frame-work and thence runs vertically and passes under a second sheave or pulley 1339 supported beneath the key-board at the rear thereof as shown in Fig. 1. The cord or pulley runs forward under the key-board and is secured to a small drum or windlass 1335 as shown more clearly in Figs. 7 and 8. This drum or windlass is mounted upon the lower end of a rotatable stud 1358 journaled in a sleeve bearing 1334 secured between the key-board plates 212 and 213. The drum is formed with an internal spline key 1335^a which engages a longitudinal groove in the stud as shown in Fig. 8 the purpose being to make the drum rotatable with the stud but to permit the latter to move longitudinally without corresponding movement of the drum. The latter and the stud both seat upon a squared portion of a cross-rod 201 and the lower key-board plate 212 extends over the drum so that the latter is held from longitudinal movement in either direction. A spring 1380 surrounds the stud within the sleeve 1334 and bears at opposite ends against shoulders of said sleeve and stud said spring thus tending to depress the latter. A thumb-piece 1333 is screwed to the upper end of the stud and there is clamped between said thumb-piece and a shoulder of the stud an index finger 1326. There is secured upon the upper key-board plate 213 a circular index plate 1325 bearing numbers from two to eight and correspondingly apertured as shown at 1325^a. The index finger 1326 has a small locating stud 1361 on its under-side which is adapted to engage any one of the apertures or depressions 1325^a. With the index finger positioned as shown in Fig. 2, midway between the numerals 2 and 8 on said index plate, the disk 1336 will be in its extreme left-hand position as shown in this figure of the drawings. The thumb-piece 1333 can be raised against the stress of the spring 1380 and the index finger stud 1361 thus disengaged from the index plate. Then by turning said thumb-piece to the right the index finger can be carried to any desired numeral on the index plate and re-engaged with the latter. This results in winding the cord or cable 1399 upon the drum or windlass 1335 and through the described connections sliding the disk 1336 to the right correspondingly positioning it over one or another of the coupler bars or levers.

It will be obvious that through the above-described means an adjustment can be effected providing for the discontinuance of coöperative relationship between any two adjacent latches and hence for the splitting of the machine between any two denominations or decimal places. It will be understood that the shifting of the presser-foot or disk cannot take place while it is depressing the forward end of one of the coupler bars

and therefore that the spring 1383 must be restrained during adjustment of the disk. It follows that the above-described manipulation merely sets or relatively positions the parts for the accomplishment of the split. Further manipulation is required to effect the split. 70

Proceeding now to a description of the devices whereby the conditions under which the machine shall operate are predetermined and referring more particularly to Figs. 1 and 3 there is secured to the rock-shaft 1302 an arm 1316 which on the forward side of said shaft is equipped with a stud 1352 occupying a slot in the left-hand side-piece 1318 of the bail hereinbefore described. On the rear side of said rock-shaft 1302 said arm is pivotally connected by a screw-stud 1354 with a vertical link 1314. The upper end of said link is pivotally connected with one arm of a bell-crank lever 1317 pivoted upon a cross-shaft 602. The other arm of said bell-crank is pivotally connected with the rear end of a bent rod 1306 slidingly engaged with a guideway on the underside of the lower key-board plate 212. The forward end of this bent rod abuts the edge of a cam plate 1321 horizontally disposed beneath the key-board and secured to the lower end of a rotatable stud 1359. The latter is journaled in a sleeve bearing 1331 secured between the key-board plates. A thumb-piece 1330 is screwed to the upper end of the stud and there is clamped between this thumb-piece and a collar 1332 an index finger 1323. A sector-shaped index plate 1324 embraces the upper end of the sleeve bearing 1331 and is fixed to the upper key-board plate in such position that the index finger 1323 may sweep over it. This index plate is marked to indicate three different positions and inscribed at said marks respectively with the abbreviations "Nor.," "Nos." and the word "Dates". The first abbreviation refers to what is termed the normal condition of the machine, that is to say a non-split condition. The second abbreviation is that of the word "numbers" and indicates a split condition of the machine under which totals will be printed for each of two sets of items, one of which may represent measure numbers and the other monetary amounts. The third inscription indicates a split condition of the machine under which a total of items composing the left-hand series is excluded from the record as in the case of day dates. The cam-plate 1321 is formed in its edge with three notches, the bases of which are graded in distance from the center of rotation of the cam-plate. A spring 1384 connected at its lower end with the link 1314 and at its upper end with a fixed stud exerts itself to lift said link and consequently thrust the bent rod 1306 against the edge of the cam-plate and enforce engagement 80 90 95 100 105 110 115 120 125 130

between the forward end of said rod and one or another of the notches of said cam-plate, (see Fig. 4). Of course the spring also pulls upwardly on the arm 1316. However, so long as the cam-plate 1321 is positioned as illustrated in Figs. 3 and 4, that is with its highest part engaging the rod 1306 said arm 1316 is restrained with its stud 1352 upholding the bail 1318 and thus keeping the disk 1336 clear of the coupler bars. So long as this adjustment obtains said disk can be slid back and forth on its rod 1303 and positioned over any one of the coupler bars but there can be no actual uncoupling of latches 15 by displacement of a coupler bar until the thumb-piece 1330 is turned to carry the index pointer 1323 away from the "normal" index mark and to one of the other marks on the index plate 1324. When the thumb-piece 20 1330 is so moved a lower part of the cam-plate 1321 is brought into engagement with the rod 1306 and the latter thus permitted to move forward. This forward movement is of course produced by the 25 spring 1384 and is accompanied by upward movement of the rear part of the arm 1316 and corresponding downward movement of the forward part of said arm. Thus the spring 1383 will be allowed to draw down 30 the bail 1318 and the disk 1336 so that the latter will displace the coupler bar immediately below it and effect the split.

The means employed for determining whether or not the left-hand section or division of the split machine shall print a total are of the following description: There is secured to the rock-shaft 1302 a hook 1320 and there is pivotally mounted upon a fixed screw-stud on the framework below the shaft 40 1301 an arm 1311 formed with a hook 1311^a under which the hook 1320 engages as shown in Fig. 3. The arm 1311 extends farther to the rear beyond its hook and at its rearward extremity carries a laterally projecting roller 1350 which overlies the tail of the last latch 45 717 to the left, (see Fig. 11). The arm 1311 has an upwardly curved forward portion 1311^b which is pivotally connected by a screw-stud 1360 with a link 1313 and the latter is slotted at its forward end to embrace 50 a stud 1357 on the lower end of a swinging arm 1312 secured to the rock-shaft 204. A retractile spring 1311^c connects the rear end of the link with a fixed stud 1311^d and tends to draw the link rearwardly and depress the arm 1311. So long as the total key 55 remains elevated the link 1313 cannot move rearwardly and hence the arm 1311 must remain at its elevated position without in any manner affecting the operation of the latches, the total key spring 288 being superior to the spring 1311^c. Furthermore, so long as the thumb-piece 1330 is at either "normal" or "numbers" position this arm 60 1311 remains inactive due to continued en-

gagement between the hooks 1320 and 1311^a. Fig. 3 as before stated illustrates the so-called normal condition and it will be observed that the hook 1320 is fully engaged beneath the hook 1311^a. When the thumb-piece 1330 is turned to the right so as to bring the index finger 1323 to the "numbers" mark the hook 1320 is moved rearwardly by reason of the connections hereinbefore described but not far enough to disengage 75 it entirely from the hook 1311^a, (see Fig. 9). When, however, the thumb-piece 1330 is moved still farther to the right and brought to the third position with the index finger at the "dates" mark then the hook 1320 will 80 have been moved entirely out of engagement with the hook 1311^a as illustrated in Fig. 10. The arm 1311 is thus relieved from the restraint imposed upon it by this hook 1320. Under these conditions when a total is to be 85 taken the arm 1311 will be entirely under control of the total key and certain restoring devices now to be described. The restoring frame 613 hereinbefore mentioned has affixed to one of its side arms an abutment piece 90 1313^a of generally triangular contour the rear edge of which abuts the shaft 600 and the forward edge of which extends behind a roller 1356 on the link 1313, (see Fig. 5). When the restoring frame 613 is in normal 95 elevated position this abutment piece holds the link 1313 forward by reason of the described engagement with the roller 1356. Of course when the restoring frame 613 swings rearwardly the link is relieved of this 100 restraint and if the total key has been depressed said link may move rearwardly and rock the arm 1311. The slot in the forward end of the link permits depression of the total key and consequently rearward 105 swinging of the arm 1312 independently of the link. The total key having been depressed and the stud 1357 thus moved to the rear end of the slot in the link the latter will then follow the abutment piece 110 1313^a as the restoring frame 613 swings rearwardly in an operation of the machine. Thus the arm 1311 will be lowered and its roller 1350 acting upon the tail of the latch 717 farthest to the left will trip the same 115 and all of the latches to the right up to the split. However, this tripping of the latches does not result in an action of the associated hammers capable of making an imprint. This is explained as follows: When 120 a total is to be printed by the operation of the left-hand section or division of the split machine the latches are tripped by the pawls 718 and this does not take place until after the restoring bail 712 has moved to the 125 upper end of its regular excursion. Consequently the springs 780 are free to instantly act upon the tripping of the latches and effect the quick blow of the hammers which is essential to the making of the imprint, it 130

being understood that there is a percussive action of the hammers. Now the tripping of the left-hand latches by the arm 1311 takes place at an early stage in the operation of the machine when the restoring bail 712 is still in engagement with the hammer drivers. Consequently the springs 780 are not free to effect the quick printing blow but the hammers simply move rearward as 5 permitted by the rise of said restoring bail. This precludes a printing action and hence under the "dates" adjustment there can be 10 no printing of totals by the left-hand section or division of the split machine. With 15 the completion of a totalizing operation the abutment piece 1313^a acting against the roller 1356 restores the link 1313 and arm 1311 to normal and of course the total key is likewise restored so that the stud 1357 remains in engagement with the forward end of 20 the slot in said link. This positive restoration of the link is not essential as the total key spring will effect the restoration, but it is considered desirable to guard against possible 25 misoperation through failure of the spring to do this work, by providing the positive restoring means described. The total key spring is not, however, thus deprived of all function in connection with the link, for it will be understood that this 30 spring operates to hold the link forward when the restoring piece retreats in an operation of the machine not accompanied by depression of the total key. The movement 35 of the thumb-piece 1330 from the "numbers" to the "dates" position does not result in any further depression of the presser-foot bail, the downward movement of the latter being limited by the abutment 40 of the displaced coupler bar or lever against the rock-shaft 1302 as shown in Fig. 9. It will be observed that as the parts are illustrated in this figure of the drawings the stud 1352 is still at the upper end of the slot 45 in the side-arm 1318 of the bail. When the arm 1316 is moved farther upward by the turning of the thumb-piece 1330 to the "dates" position said stud simply moves to the bottom of the slot as illustrated in Fig. 50 10. It may be added in this connection that when the bail and its presser-foot are depressed, accompanying arc-movement of the rod 1304 is permitted by the before-mentioned slot 1303^a in the guiding boss 1304^a 55 for said rod.

It is to be understood that the construction here disclosed is susceptible of various modifications within the scope of the invention.

60 What is claimed is:

1. In a machine of the character described, the combination of a series of impression means coöperatively related for the printing of ciphers to right of numerals in decimal places where the amount to be recorded has 65

no units, with provisions for discontinuing the coöperative relationship between adjacent members of the series of impression means; and manipulative means controlling said coöperative relationship and adjustable 70 to effect discontinuance thereof between one or another pair of adjacent members of the series of impression means with provisions for predetermining whether or not one division of said means shall be effective to make 75 impressions when thus out of coöperative relationship with the other division.

2. In a machine of the character described, the combination of a series of impression means coöperatively related for the printing 80 of ciphers to right of numerals in decimal places where the amount to be recorded has no units, with provisions for discontinuing the coöperative relationship between adjacent members of the series of impression 85 means; type; means for setting up the same; an accumulator; totaling connections between the latter and the type; and manipulative means controlling coöperative relationship between the members of the impression means and adjustable to effect discontinuance thereof between one or another 90 pair of adjacent members with provisions for predetermining whether or not one division of said means shall be effective to make 95 impressions when thus out of coöperative relationship with the other division.

3. In a machine of the character described, the combination of a series of impression means coöperatively related for the printing 100 of ciphers to right of numerals in decimal places where the amount to be recorded has no units, with provisions for discontinuing the coöperative relationship between adjacent members of the series of impression means; type; means for setting up the same; an accumulator; totaling connections between the latter and the type; and manipulative means controlling coöperative relationship between the members of the impression means and adjustable to effect discontinuance thereof between one or another 105 pair of adjacent members with provisions for predetermining whether or not one division of said means shall be effective to make 110 impressions when thus out of coöperative relationship with the other division.

4. In a machine of the character described, the combination of a series of separately acting impression devices; movable couplers between the members of said series for securing coöperative action between the same in the printing of ciphers; a coupler-displacing device adjustable among the couplers; and means for operating said displacing device.

5. In a machine of the character described, the combination of a series of separately acting impression devices; movable 130

couplers between the members of said series for securing coöperative action between the same in the printing of ciphers; a coupler-displacing device adjustable among the couplers; and means for operating said displacing device with provisions for predetermining whether or not one division of the impression devices shall be effective to make impressions when uncoupled from another division.

6. In a machine of the character described, the combination of a series of separately acting impression devices; movable couplers between the members of said series for securing coöperative action between the same in the printing of ciphers; type; means for setting up the same; an accumulator; totaling connections between the latter and the type; a coupler-displacing device adjustable among the couplers; and means for operating said displacing device.

7. In a machine of the character described, the combination of a series of separately acting impression devices; movable couplers between the members of said series for securing coöperative action between the same in the printing of ciphers; type; means for setting up the same; an accumulator; totaling connections between the latter and the type; a coupler-displacing device adjustable among the couplers; and means for operating said displacing device with provisions for predetermining whether or not one division of the impression devices shall be effective to make impressions when uncoupled from another division.

8. In a machine of the character described, the combination of a series of separately acting impression devices; movable couplers between the members of said series for securing coöperative action between the same in the printing of ciphers; a coupler-displacing device adjustable among the couplers; and manipulative means for rendering said displacing device effective or ineffective at will.

9. In a machine of the character described, the combination of a series of separately acting impression devices; movable couplers between the members of said series for securing coöperative action between the same in the printing of ciphers; a coupler-displacing device adjustable among the couplers; and manipulative means for rendering said displacing device effective or ineffective at will with provisions for preventing the making of impressions while the displacing device is effective.

10. In a machine of the character described, the combination of a series of separately acting impression devices; movable couplers between the members of said series for securing coöperative action between the same in the printing of ciphers; type; means for setting up the same; an accumulator;

totaling connections between the latter and the type; a coupler-displacing device adjustable among the couplers; and manipulative means for rendering said displacing device effective or ineffective at will.

11. In a machine of the character described, the combination of a series of separately acting impression devices; movable couplers between the members of said series for securing coöperative action between the same in the printing of ciphers; type; means for setting up the same; an accumulator; totaling connections between the latter and the type; a coupler-displacing device adjustable among the couplers; and manipulative means for rendering said displacing device effective or ineffective at will with provisions for preventing the making of impressions while the displacing device is effective.

12. In a machine of the character described, the combination of sets of type, setting up devices for the same, hammers for the respective sets of type, latches holding the hammers normally retracted, means for severally displacing the latches in an operation of the machine, movable couplers between the latches for securing coöperative action in the printing of ciphers, a coupler-displacing device adjustable among the couplers; and means for operating said displacing device.

13. In a machine of the character described, the combination of sets of type, setting up devices for the same, hammers for the respective sets of type, latches holding the hammers normally retracted, means for severally displacing the latches in an operation of the machine, movable couplers between the latches for securing coöperative action in the printing of ciphers, a coupler-displacing device adjustable among the couplers, and means for operating said displacing device with provisions for predetermining whether or not one division of the hammers shall be effective to make impressions when its latches are uncoupled, from those of another division of hammers.

14. In a machine of the character described, the combination of sets of type, setting up devices for the same, hammers for the respective sets of type, latches holding the hammers normally retracted, means for severally displacing the latches in an operation of the machine, movable couplers between the latches for securing coöperative action in the printing of ciphers, a coupler-displacing device adjustable among the couplers; and manipulative means for rendering said displacing device effective or ineffective at will.

15. In a machine of the character described, the combination of sets of type, setting up devices for the same, hammers for the respective sets of type, latches holding the hammers normally retracted, means

- for severally displacing the latches in an operation of the machine, movable couplers between the latches for securing coöperative action in the printing of ciphers, a coupler-displacing device adjustable among the couplers; and manipulative means for rendering said displacing device effective or ineffective at will with provisions for preventing the making of impressions while the displacing device is effective. 70
16. In a machine of the character described, the combination of sets of type, setting up devices therefor; an accumulator, totaling connections between the latter and the type, hammers for the respective sets of type, latches holding the hammers normally retracted, means for severally displacing the latches in an operation of the machine, movable couplers between the latches for securing coöperative action in the printing of ciphers, a coupler-displacing device adjustable among the couplers; and means for operating said displacing device. 80
17. In a machine of the character described, the combination of sets of type, setting up devices therefor; an accumulator, totaling connections between the latter and the type, hammers for the respective sets of type, latches holding the hammers normally retracted, means for severally displacing the latches in an operation of the machine, movable couplers between the latches for securing coöperative action in the printing of ciphers, a coupler-displacing device adjustable among the couplers; and means for operating said displacing device with provisions for predetermining whether or not one division of the hammers shall be effective to make impressions when its latches are uncoupled from those of another division of hammers. 90
18. In a machine of the character described, the combination of sets of type, setting up devices therefor; an accumulator, totaling connections between the latter and the type, hammers for the respective sets of type, latches holding the hammers normally retracted, means for severally displacing the latches in an operation of the machine, movable couplers between the latches for securing coöperative action in the printing of ciphers, a coupler-displacing device adjustable among the couplers; and manipulative means for rendering said displacing device effective or ineffective at will. 95
19. In a machine of the character described, the combination of sets of type, setting up devices therefor; an accumulator, totaling connections between the latter and the type, hammers for the respective sets of type, latches holding the hammers normally retracted, means for severally displacing the latches in an operation of the machine, movable couplers between the latches for securing coöperative action in the printing of ciphers. 100
20. In a machine of the character described, the combination of sets of type, setting up devices therefor; an accumulator, totaling connections between the latter and the type, hammers for the respective sets of type, latches holding the hammers normally retracted, means for severally displacing the latches in an operation of the machine, movable couplers between the latches for securing coöperative action in the printing of ciphers, means for selectively displacing the couplers to discontinue coöperative relationship between any two adjacent latches; and means under control of the totaling connections for so displacing the latches of one division when uncoupled from the latches of another division, as to prevent the hammers of the first-named division from making impressions. 105
21. In a machine of the character described, the combination of sets of type, setting up devices therefor; an accumulator, totaling connections between the latter and the type, hammers for the respective sets of type, latches holding the hammers normally retracted, means for severally displacing the latches in an operation of the machine, movable couplers between the latches for securing coöperative action in the printing of ciphers, a coupler-displacing device adjustable among the couplers; means for operating said displacing device; and means under control of the totaling connections for so displacing the latches of one division when uncoupled from the latches of another division, as to prevent the hammers of the first-named division from making impressions. 110
22. In a machine of the character described, the combination of sets of type, setting up devices therefor; an accumulator, totaling connections between the latter and the type, hammers for the respective sets of type, latches holding the hammers normally retracted, means for severally displacing the latches in an operation of the machine, movable couplers between the latches for securing coöperative action in the printing of ciphers, a coupler-displacing device adjustable among the couplers; manipulative means for rendering said displacing device effective or ineffective at will; and means under control of the totaling connection for so displacing the latches of one division when uncoupled from the latches of another division, as to prevent the hammers of the first-named division from making impressions. 115
23. In a machine of the character de- 120
- 125
- 130

- scribed, the combination of sets of type, setting up devices therefor; an accumulator, totaling connections between the latter and the type, hammers for the respective sets of type, latches holding the hammers normally retracted, means for severally displacing the latches in an operation of the machine, movable couplers between the latches for securing coöperative action in the printing of ciphers, a coupler-displacing device adjustable among the couplers; manipulative means for rendering said displacing device effective or ineffective at will, a latch-displacing device under control of the totaling connections, a latch for said latch-displacing device under control of the manipulative means for rendering the coupler-displacing device effective or ineffective, and a reciprocating restorer for said latch-displacing device adapted in its initial movement to permit action of the latter, substantially as and for the purpose described.
- 5 24. In a machine of the character described, the combination of sets of type, setting up devices therefor; an accumulator, totaling connections between the latter and the type, hammers for the respective sets of type, latches holding the hammers normally retracted, means for severally displacing the latches in an operation of the machine, movable couplers between the latches for securing coöperative action in the printing of ciphers, a coupler-displacing device adjustable among the couplers, means for operating said displacing device, a latch-displacing device under control of the totaling connections, and a reciprocating restorer for said latch-displacing device adapted in its initial movement to permit action of the latter, substantially as and for the purpose described.
- 10 25. In a machine of the character described, the combination of sets of type, setting up devices therefor; an accumulator, totaling connections between the latter and the type, hammers for the respective sets of type, latches holding the hammers normally retracted, means for severally displacing the latches in an operation of the machine, movable couplers between the latches for securing coöperative action in the printing of ciphers, a coupler-displacing device adjustable among the couplers, means for rendering said displacing device effective or ineffective at will, a latch-displacing device under control of the totaling connections, and a reciprocating restorer for said latch-displacing device adapted in its initial movement to permit action of the latter, substantially as and for the purpose described.
- 15 26. In a machine of the character described, the combination of sets of type, setting up devices therefor; an accumulator, totaling connections between the latter and the type, hammers for the respective sets of type, latches holding the hammers normally retracted, means for severally displacing the latches in an operation of the machine, movable couplers between the latches for securing coöperative action in the printing of ciphers, a coupler-displacing device adjustable among the couplers; manipulative means for rendering said displacing device effective or ineffective at will, a latch-displacing device under control of the totaling connections, a latch for said latch-displacing device under control of the manipulative means for rendering the coupler-displacing device effective or ineffective, and a reciprocating restorer for said latch-displacing device adapted in its initial movement to permit action of the latter, substantially as and for the purpose described.
- 20 27. In a machine of the character described, the combination of sets of type, setting up devices for the same, hammers for the respective sets of type, latches holding the hammers normally retracted, means for severally displacing the latches in an operation of the machine, movable couplers between the latches for securing coöperative action in the printing of ciphers, said couplers being in the form of levers each equipped to simultaneously engage two adjacent latches, a presser-foot laterally adjustable for coöperation with any one of said levers, manipulative means for so adjusting said presser-foot, and other manipulative means for actuating the presser-foot when adjusted and displacing one of the levers to uncouple adjacent latches.
- 25 28. In a machine of the character described, the combination of sets of type, setting up devices for the same, hammers for the respective sets of type, latches holding the hammers normally retracted, means for severally displacing the latches in an operation of the machine, movable couplers between the latches for securing coöperative action in the printing of ciphers, said couplers being in the form of levers each equipped to simultaneously engage two adjacent latches, a vibratory bail, a presser-foot laterally movable thereon for coöperation with any one of said levers, manipulative means for so moving said presser-foot, and other manipulative means for actuating the bail and thus displacing one of the levers to uncouple adjacent latches.
- 30 29. In a machine of the character described, the combination of sets of type, setting up devices for the same, hammers for the respective sets of type, latches holding the hammers normally retracted, means for severally displacing the latches in an operation of the machine, movable couplers between the latches for securing coöperative action in the printing of ciphers, said couplers being in the form of levers each equipped to simultaneously engage two adjacent latches, a presser-foot spring-drawn in one direction laterally of the levers,

manipulative means for moving said presser-foot progressively in opposition to the spring, and other manipulative means for actuating the presser-foot to displace the coupler lever with reference to which it has been adjusted.

30. In a machine of the character described, the combination of sets of type, setting up devices for the same, hammers for the respective sets of type, latches holding the hammers normally retracted, means for severally displacing the latches in an operation of the machine, movable couplers between the latches for securing coöperative action in the printing of ciphers, said couplers being in the form of levers each equipped to simultaneously engage two adjacent latches, a vibratory bail, a presser-foot laterally movable thereon for coöperation with any one of said levers, a spring impelling said presser-foot one way, manipulative means for moving the presser-foot progressively against the stress of said spring, and other manipulative means for actuating the bail and thus displacing one of the levers to uncouple adjacent latches.

31. In a machine of the character described, the combination of sets of type, setting up devices for the same, hammers for the respective sets of type, latches holding the hammers normally retracted, means for severally displacing the latches in an operation of the machine, movable couplers between the latches for securing coöperative action in the printing of ciphers, said couplers being in the form of levers each equipped to simultaneously engage two adjacent latches, a presser-foot spring-drawn in one direction laterally of the levers, a cable connected with said presser-foot, a drum to which said cable is attached, a pointer compounded with said drum, a dial, a handle by which to turn the drum and pointer, and means for actuating the presser-foot to displace one of the coupler levers.

32. In a machine of the character described, the combination of sets of type, setting up devices for the same, hammers for the respective sets of type, latches holding the hammers normally retracted, means for severally displacing the latches in an operation of the machine, movable couplers between the latches for securing coöperative action in the printing of ciphers, said couplers being in the form of levers each equipped to simultaneously engage two adjacent latches, a vibratory bail, a presser-foot laterally movable thereon for coöperation with any one of said levers, a spring impelling said presser-foot one way, a cable connected with said presser-foot, a drum to which said cable is attached, a pointer compounded with said drum, a dial, a handle by which to turn the drum and pointer, and

means for actuating the bail to displace one of the coupler levers by the action of the presser-foot thereagainst.

33. In a machine of the character described, the combination of sets of type, setting up devices for the same, hammers for the respective sets of type, latches holding the hammers normally retracted, means for severally displacing the latches in an operation of the machine, movable couplers between the latches for securing coöperative action in the printing of ciphers, said couplers being in the form of levers each equipped to simultaneously engage two adjacent latches, a presser-foot spring-drawn in one direction laterally of the levers, a cable connected with said presser-foot, a drum to which said cable is attached, a rotatable knob splined to said drum, a pointer compounded with said knob, a dial with locating depressions for the pointer, a spring enforcing engagement between pointer and dial, and means for actuating the presser-foot after adjustment by the turning of the knob, substantially as and for the purpose described.

34. In a machine of the character described, the combination of sets of type, setting up devices for the same, hammers for the respective sets of type, latches holding the hammers normally retracted, means for severally displacing the latches in an operation of the machine, movable couplers between the latches for securing coöperative action in the printing of ciphers, said couplers being in the form of levers each equipped to simultaneously engage two adjacent latches, a vibratory bail, a presser-foot laterally movable thereon for coöperation with any one of said levers, a spring impelling said presser-foot one way, a cable connected with said presser-foot, a drum to which said cable is attached, a rotatable knob splined to said drum, a pointer compounded with said knob, a dial with locating depressions for the pointer, a spring enforcing engagement between pointer and dial, and means for actuating the bail after adjustment of the presser-foot by the turning of the knob.

35. In a machine of the character described, the combination of sets of type, setting up devices for the same, hammers for the respective sets of type, latches holding the hammers normally retracted, means for severally displacing the latches in an operation of the machine, movable couplers between the latches for securing coöperative action in the printing of ciphers, said couplers being in the form of levers each equipped to simultaneously engage two adjacent latches, a disk slideable upon the bail and adapted to engage one or another of said levers, a rod connected with said disk, a spring surrounding the rod and impelling

the disk toward one side of the bail, a cable connected with the rod, guide-pulleys or sheaves for said cable, a drum to which said cable is attached, a rotatable and longitudinally movable knob and stud splined to said drum, a pointer compounded with said knob and having a lug, a fixed dial plate having a series of depressions or holes for said pointer lug to engage, and means for actuating the bail after adjustment of the roll, substantially as and for the purpose described.

36. In a machine of the character described, the combination of sets of type, setting up devices for the same, hammers for the respective sets of type, latches holding the hammers normally retracted, means for severally displacing the latches in an operation of the machine, movable couplers between the latches for securing coöperative action in the printing of ciphers, said couplers being in the form of levers each equipped to simultaneously engage two adjacent latches, a vibratory bail, a presser-foot laterally movable thereon for coöperation with any one of said levers, manipulative means for so moving said presser-foot, a thrust-rod operatively connected with the bail to vibrate the same, and a swiveled cam-plate engaging said thrust-rod and equipped for manipulation.

37. In a machine of the character described, the combination of sets of type, setting up devices for the same, hammers for the respective sets of type, latches holding the hammers normally retracted, means for severally displacing the latches in an operation of the machine, movable couplers between the latches for securing coöperative action in the printing of ciphers, said couplers being in the form of levers each equipped to simultaneously engage two adjacent latches, a vibratory bail, a presser-foot laterally movable thereon for coöperation with any one of said levers, manipulative means for so moving said presser-foot, a bell-crank lever, a link connected with one arm thereof and cranked to the bail, a thrust-rod connected with the other arm of said bell-crank lever, and a swiveled cam-plate engaging said thrust-rod and equipped for manipulation.

38. In a machine of the character described, the combination of sets of type, setting up devices for the same, hammers for the respective sets of type, latches holding the hammers normally retracted, means for severally displacing the latches in an operation of the machine, movable couplers between the latches for securing coöperative action in the printing of ciphers, said couplers being in the form of levers each equipped to simultaneously engage two adjacent latches, a vibratory bail, a presser-foot laterally movable thereon for coöperation with any one of said levers, manipulative means for so moving said presser-foot, a bell-crank lever, a link connected with one arm thereof and cranked to the bail, a

tion with any one of said levers, manipulative means for so moving said presser-foot, a thrust-rod operatively connected with the bail to vibrate the same, a swiveled cam-plate engaging said thrust-rod, a knob and pointer compounded with said cam-plate, and a dial.

39. In a machine of the character described, the combination of sets of type, setting up devices for the same, hammers for the respective sets of type, latches holding the hammers normally retracted, means for severally displacing the latches in an operation of the machine, movable couplers between the latches for securing coöperative action in the printing of ciphers, said couplers being in the form of levers each equipped to simultaneously engage two adjacent latches, a vibratory bail, a presser-foot laterally movable thereon for coöperation with any one of said levers, manipulative means for so moving said presser-foot, a bell-crank lever, a link connected with one arm thereof and cranked to the bail, a thrust-rod connected with the other arm of said bell-crank lever, a swiveled cam-plate engaging said thrust-rod, a knob and pointer compounded with said cam-plate, and a dial.

40. In a machine of the character described, the combination of sets of type, setting up devices for the same, hammers for the respective sets of type, latches holding the hammers normally retracted, means for severally displacing the latches in an operation of the machine, movable couplers between the latches for securing coöperative action in the printing of ciphers, said couplers being in the form of levers each equipped to simultaneously engage two adjacent latches, a vibratory bail, a presser-foot laterally movable thereon for coöperation with any one of said levers, manipulative means for so moving said presser-foot, a thrust-rod operatively connected with the bail to vibrate the same, and a swiveled cam-plate engaging said thrust-rod and equipped for manipulation and formed with retaining notches.

41. In a machine of the character described, the combination of sets of type, setting up devices for the same, hammers for the respective sets of type, latches holding the hammers normally retracted, means for severally displacing the latches in an operation of the machine, movable couplers between the latches for securing coöperative action in the printing of ciphers, said couplers being in the form of levers each equipped to simultaneously engage two adjacent latches, a vibratory bail, a presser-foot laterally movable thereon for coöperation with any one of said levers, manipulative means for so moving said presser-foot, a bell-crank lever, a link connected with one arm thereof and cranked to the bail, a

- thrust-rod connected with the other arm of said bell-crank lever, and a swiveled cam-plate engaging said thrust-rod and equipped for manipulation and formed with retaining notches.
42. In a machine of the character described, the combination of sets of type, setting up means therefor, hammers to strike the type, means for retracting the hammers, 10 latches for restraining the hammers, couplings between the latches for securing co-operative action in cipher-printing, means for severally tripping the latches, manipulative devices for uncoupling adjacent 15 latches comprising a bail and a laterally adjustable presser-foot carried thereby, an accumulator, totaling connections between the latter and the type, a pivoted arm equipped for engagement with the latch 20 farthest to the left, a spring drawing said arm in a direction to trip said latch, a total key controlling said totaling connections, a swinging arm operated by said key, a link connected with the latch-tripping 25 arm and having a slot-and-pin connection with said total key arm, a vibrating member for moving the link and latch-tripping arm in opposition to the spring, and a catch engaging said arm and having a slot-and-pin 30 connection with the latch-uncoupling bail.
43. In a machine of the character described, the combination of sets of type, setting up means therefor, hammers to strike the type, spring-actuated hammer drivers, 35 means for retracting the latter and the hammers, latches for restraining the drivers and consequently the hammers, couplings between the latches for securing co-operative action in cipher-printing, means for severally 40 tripping the latches, manipulative devices for uncoupling adjacent latches comprising a bail and a laterally adjustable presser-foot carried thereby, an accumulator, totaling connections between the latter and 45 the type, a pivoted arm equipped for engagement with the latch farthest to the left, a spring drawing said arm in a direction to trip said latch, a total key controlling said totaling connections, a swinging arm operated by said key, a link connected with the latch-tripping 50 arm and having a slot-and-pin connection with said total key arm, a vibrating member for moving the link and latch-tripping arm in opposition to the spring, and a catch engaging said arm and having a slot-and-pin 55 connection with the latch-uncoupling bail.

having a slot-and-pin connection with the latch-uncoupling bail.

44. In a machine of the character described, the combination of sets of type, setting up means therefor, hammers to strike 60 the type, spring-actuated hammer drivers, a vibrating bail for retracting the latter and the hammers, latches for restraining the drivers and consequently the hammers, couplings between the latches for securing co-operative action in cipher-printing, means for severally tripping the latches, manipulative devices for uncoupling adjacent 65 latches comprising a bail and a laterally adjustable presser-foot carried thereby, an 70 accumulator, totaling connections between the latter and the type, a pivoted arm equipped for engagement with the latch farthest to the left, a spring drawing said arm in a direction to trip said latch, a total 75 key controlling said totaling connections, a swinging arm operated by said key, a link connected with the latch-tripping arm and having a slot-and-pin connection with the latch-uncoupling bail.

45. In an adding machine, in combination, multiple order adding mechanism and percussive digital type-impression mechanism and optionally operable means adapted selectively and at the will of the operator to prevent the percussive action of the digital type-impression mechanism in a varying 80 plurality of orders.

46. In a machine of the character described, the combination of means for percussively printing numbers side by side, and 85 means for effecting at will a gradual release of a predetermined division of such printing means to eliminate imprints.

47. In a machine of the character described, the combination of means for percussively printing numbers side by side, and 90 means for effecting at will a gradual release of a varying predetermined division of such printing means to eliminate imprints.
